UNITED STATES PATENT OFFICE.

ARTHUR FRANCIS BERRY, OF EALING, ENGLAND.

APPARATUS FOR DISTRIBUTING ALTERNATING CURRENTS.

No. 796,555.

Specification of Letters Patent.

Patented Aug. 8, 1905.

Application filed November 6, 1903. Serial No. 180,102.

To all whom it may concern:

Be it known that I, ARTHUR FRANCIS BERRY, a subject of the King of Great Britain and Ireland, residing at Ealing, in the county of Middlesex, England, have invented Improvements in and Relating to Apparatus for Distributing Alternating Currents, of which the following is a specification.

In the distribution of alternating electric current by means of stationary transformers supplying a distributing system the load upon which is subject to considerable variation it has heretofore been proposed, with the object of reducing magnetizing losses when the load on the distributing system is low, to employ in conjunction with one or more main stationary transformers at each transforming-point a separate and special static transformer (hereinafter called, for distinction, the "supplementary" transformer) that will usually be of less size than the main transformer or transformers and also means (hereinafter called, for distinction, "short-circuiting" means) whereby the primary and secondary windings of the supplementary transformer can be coupled in series with the primary and secondary windings, respectively, of the main transformer, or of each main transformer, when the load does not exceed a predetermined amount, and whereby the windings of the said supplementary transformer can be short-circuited as soon as the load increases beyond the capacity of the supplementary transformer, the main transformer or transformers being then alone used. In such earlier arrangements the short-circuiting means have been operated at the required times either by hand or automatically by an electromagnetic device having a high resistance winding constantly in the secondary circuit.

The first-mentioned arrangement requires the constant presence of an attendant, while the second arrangement results in a constant and serious loss of energy in the electromagnetic device.

The present invention has for object to enable the short-circuiting means to be operated automatically and by electromagnetic means that are only brought temporarily into circuit, so that it will not be liable to be injured by undue heating and will not cause waste of energy. For this purpose there is used in conjunction with short-circuiting means, such as switches for short-circuiting the primary and secondary winding of the

supplementary transformer and putting the same out of action when the load on the distributing system increases beyond a predetermined amount and for open-circuiting the said windings, so as to place them in series with the main transformer or transformers when the load falls below the said predetermined amount, an electromagnetic device for operating the said short-circuiting means and an electrically-operated switch or relay apparatus having its winding arranged in the primary or secondary circuit of the distributing system and adapted to connect the electromagnetic device across a source of electric energy and cause it to operate the short-circuiting means in one direction or the other, according as the load falls below or rises above the predetermined amount, the arrangement being such that the electromagnetic device after being brought into action to operate the short-circuiting means in one direction or the other will be immediately cut out of action, so as to prevent its being injured by undue heating and also to prevent waste of energy. The winding of the electrically-operated switch is preferably arranged in the primary circuit, so that it can be constructed to absorb very little energy and can be used as an indicator to continually show the load on the primary circuit, and consequently that on the secondary circuit.

The electrically-operated switch and short-circuiting means and the electromagnetic device for operating the short-circuiting means under the control of the electrically-operated switch can be constructed in various forms.

The accompanying drawing shows diagrammatically a transforming-station having main and supplementary transformers arranged for use, as hereinbefore described, together with a constructional arrangement of short-circuiting means, an electromagnetic device for actuating the said short-circuiting means, and an electrically-operated switch for automatically putting the supplementary transformer in and out of series connection with the main transformer or transformers to suit the conditions of working.

1 and 2 are the primary or high-tension leads, and 3 and 4 the secondary or lower-tension distributing-leads.

5 represents the primary windings, and 6 the secondary windings, of a number of large transformers, the primary windings 5 being connected at one end through switches 7 to a common conductor 8 and at the other end to

the primary lead 2 and the secondary windings 6 being connected at one end through switches 9 to a common conductor 10 and at the other end to the secondary lead 4.

11 and 12 are respectively the primary and secondary windings of the supplementary transformer, the primary winding 11 having one of its ends connected to the primary lead 1 and the other to the conductor 8 and the secondary winding 12 having one of its ends connected to the secondary lead 3 and the other to the conductor 10.

The electrically-operated switch comprises an electromagnet having a hollow core 36 and a winding 37 in series with the primary lead 1, an armature 38, acted upon by a spring 39, that tends to move it away from the concentric poles of the electromagnet, two movable switch-contacts 40 and 41, and three flexible fixed contacts 47, 48, and 49, the several contacts being insulated from each other. The movable contacts 40 and 41 are in the form of two levers that are insulated from each other, are electrically connected to the secondary leads 3 and 4, respectively, by conductors 40^a and 41^a, and are mechanically connected to the armature 38 in such a way that when the armature moves toward or from the said poles they will be respectively moved into the positions shown in full and dotted lines. For this purpose the armature 38 is connected to a rod 42, that is provided with a tubular holder 42^a for a spring 42^b, that is arranged between and connected to the adjacent ends of the levers 40 and 41 for the purpose of moving them in one direction or the other, according to the direction of movement of the armature 38, and of causing them after passing the mid-position in either direction to quickly complete their movement.

43 is a switch-lever carrying a movable contact 43^a, arranged to be inserted between and withdrawn from spring-contacts 13 and 16, connected, respectively, to the primary lead 1 and conductor 8 for the purpose of controlling the circuit of the primary winding 11, and 44 is a similar lever carrying a movable contact 44^a, coöperating in the same way with the contacts 14 and 17, connected to the secondary lead 3 and conductor 10 for controlling the circuit of the secondary winding 12, these parts constituting the short-circuiting means hereinbefore referred to. The contacts 43^a 44^a are insulated from their carrying-levers 43 44, as shown.

The electromagnetic device for operating the switch-levers comprises an electromagnet having a stationary hollow cylindrical core 45, two windings 46 46^a, arranged within the said core and connected, respectively, to the insulated spring-contacts 47 and 48 and also connected together at the point 46^b and to the insulated spring-contact 49, which is common to them, and two movable armatures 50 and 50^a, that are rigidly connected together

through a piece 50^b of non-magnetic material—for example, brass—and also to the levers 43 and 44 through links 51, made of insulating material, the said levers 43 and 44 thus being insulated from each other. The contacts 47 and 48 are arranged in the path of the long arm of lever 40 and are separated from each other by a strip of insulating material 51. The contact 49 is arranged in the path of the long arm of the lever 41.

The operation of the arrangement is as follows: Assuming the load on the system to be below the predetermined limit and the supplementary transformer to be in circuit, so that the movable parts of the electrically-operated switch, electromagnetic actuating device, and short-circuiting means are in the positions shown in dotted lines, then when the current in the primary mains 1 and 2 exceeds the predetermined limit the armature 38 of the electrically-controlled switch will be attracted by the electromagnet 36 37 against the action of the spring 39, so to move the contact-levers 40 and 41 from the positions shown in dotted lines to those shown in full lines. The said levers in their movement will bear momentarily and simultaneously against the contacts 48 and 49, respectively, with the result that the coil 46^a will be momentarily coupled across the leads 3 and 4 and the armatures 50 50^a will be moved into the position shown in full lines, so as to cause the movable contacts 43^a and 44^a, carried by the switch-levers 43 and 44, to be inserted, respectively, between the contacts 13 16 and 14 17 and short-circuit the primary and secondary windings 11 and 12 of the supplementary transformer, so that the main transformer or transformers will alone be in action. When the current in the primary leads 1 and 2 falls below the predetermined extent, the armature 38 will be caused by the spring 39 to move away from the poles of the electromagnet 36 37, and thereby move the contact-levers 40 and 41 in the reverse direction and into the positions shown in dotted lines, the said contact-levers during their movement bearing momentarily and simultaneously against the contacts 47 and 49, with the result that a momentary current will be sent through the coil 46, whereby the armatures 50 50^a will be moved in the opposite direction and into the positions shown in dotted lines, so as to withdraw the movable contacts 43^a 44^a, carried by the switch-levers 43 and 44, from between the contacts 13 16 and 14 17 and open-circuit the windings 11 and 12 of the supplementary transformer, so as to bring them into series circuit with the primary and secondary windings 5 and 6, respectively, of the main transformers.

The high and low tension windings 11 and 12 of the supplementary transformer can, if desired, after being short-circuited be disconnected from the high and low tension leads, respectively.

The main and supplementary transformers

may of course be arranged to transform either down or up, as required.

What I claim is—

1. In apparatus for distributing alternating electric current, the combination with one or more main transformers, of a supplementary transformer, short-circuiting means whereby the primary and secondary windings of the supplementary transformer can be coupled in series with the primary and secondary windings respectively of the main transformer, or of each main transformer, when the load does not exceed a predetermined amount and whereby the windings of the said supplementary transformer can be short-circuited when the load increases beyond a predetermined amount, electromagnetic means adapted to operate said short-circuiting means, and means whereby said electromagnetic means can be caused to become energized in a temporary manner so as to actuate the short-circuiting means in one or other direction when the load rises above or falls below the predetermined amount.

2. In an alternating-current-distributing system, the combination with one or more main transformers, of a supplementary transformer, switch mechanism whereby the primary and secondary windings of said supplementary transformer can be either short-circuited or placed in series respectively with the primary and secondary windings of the main transformer or transformers, a normally open circuited electromagnetic device adapted to actuate said switch mechanism, and means whereby said electromagnetic device can be temporarily energized and caused to operate said switch mechanism in one direction or the other when the demand on the system rises above or falls below a predetermined amount.

3. In an alternating-current-distributing system, the combination with one or more main transformers, of a supplementary transformer, switch mechanism whereby the primary and secondary windings of said supplementary transformer can be short-circuited or placed in series respectively with the primary and secondary windings of the main transformer or transformers, a relay continually controlled by current flowing through a part of the distributing system, and an electromagnetic device adapted to be temporarily energized by the action of said relay and arranged to operate said switch mechanism to short-circuit or open-circuit the windings of the supplementary transformer according as the demand on the said system rises above or falls below a predetermined amount.

4. In an alternating-current-distributing system, the combination with one or more main transformers, of a supplementary transformer, switch mechanism whereby its primary and secondary windings can be short-circuited or put in series respectively with the primary and secondary windings of the main

transformer or transformers, electromagnetic means normally on open circuit and adapted when energized to automatically cause the operation of said switch mechanism, a source of electric energy, and a relay subject to variation in the electric supply and adapted to cause said electromagnetic device to be momentarily connected across said source of electric energy when the load on the system falls below or rises above a predetermined amount.

5. In an alternating-current-distributing system, the combination with one or more main transformers, of a supplementary transformer, switch mechanism whereby the primary and secondary windings of said supplementary transformer can be short-circuited or placed in series respectively with the primary and secondary windings of the main transformer or transformers, a source of electric energy, an electromagnetic device having two separate normally open windings arranged to be connected one at a time across said source of electric energy and adapted to operate said switches in one direction or the other, and a relay arranged in one of the distributing-circuits and adapted to operate when the load on the system rises above or falls below a predetermined amount and momentarily close the circuit of one or other of the two windings.

6. In an alternating-current-distributing system, the combination with one or more main transformers, of a supplementary transformer, switch mechanism whereby the primary and secondary windings of said supplementary transformer can be short-circuited or placed in series respectively with the primary and secondary windings of the main transformer or transformers, a normally open-circuited double-acting electromagnetic device adapted, when energized, to actuate said switch mechanism in one or other direction, and an electrically-controlled switch having its winding arranged in the primary circuit of the said system and adapted, when the load rises above or falls below a predetermined amount, to cause the circuit of one or other of the windings of the electromagnetic device to be closed across the secondary circuit of the system and thereby cause the said device to actuate the switch mechanism in the proper direction to respectively short-circuit or open-circuit the windings of the supplementary transformer.

7. In an alternating-current-distributing system, the combination with primary and secondary leads, of a supplementary transformer having its primary winding connected at one end to one of the primary leads and its secondary winding connected at one end to one of the secondary leads, one or more main transformers having or each having its primary winding connected at one end to the other primary lead and adapted to be connected at the other end to the second end of

the supplementary primary winding and its secondary winding connected at one end to the other secondary lead and adapted to be connected at the other end to the second end of the supplementary secondary winding, switches adapted to short-circuit and to open-circuit the windings of the supplementary transformer, a relay having its winding in one of the circuits so as to be subject to variation of electrical conditions therein, and a double-acting electromagnetic device adapted to actuate said switches and arranged to be temporarily connected across one of the pairs of leads by the relay when the load rises above or falls below a predetermined amount.

8. In an alternating-current-distributing system, the combination with primary and secondary leads, of a supplementary transformer having its primary winding connected at one end to one of the primary leads and its secondary winding connected at one end to one of the secondary leads, one or more main transformers having or each having its primary winding connected at one end to the other primary lead and adapted to be connected at the other end to the second end of the supplementary primary winding and its secondary winding connected at one end to the other secondary lead and adapted to be connected at the other end to the second end of the supplementary secondary winding, switches adapted to short-circuit and to open-circuit the windings of the supplementary transformer, an electrically-controlled switch having its winding in series with the primary lead to which the primary winding of said supplementary transformer is connected, and a double-acting electromagnetic device connected to said switches and adapted to be temporarily connected across the secondary leads by said electrically-controlled switch and thereby caused to operate in one or other direction, upon increase or decrease of current in said primary lead above or below a predetermined amount.

9. In an alternating-current-distributing system, the combination with primary and secondary leads, of a supplementary transformer having its primary winding connected at one end to one of the primary leads and its secondary winding connected at one end to one of the secondary leads, one or more main transformers having or each having its primary winding connected at one end to the other primary lead and adapted to be connected at the other end to the second end of the supplementary primary winding and its secondary winding connected at one end to the other secondary lead and adapted to be connected at the other end to the second end of

the supplementary secondary winding, switch-contacts connected to the ends of the supplementary primary winding and a switch-lever adapted to connect and disconnect said switch-contacts, switch-contacts connected to the ends of the supplementary secondary winding and a switch-lever adapted to connect and disconnect these switch-contacts, a reciprocatory electromagnetic device having two separate windings each adapted to be alternately connected across the secondary circuit and a double-acting armature connected to said switch-levers, and adapted to be moved in one or other direction according to the winding that is connected across the secondary circuit, and an electrically-controlled switch having its winding arranged in one of the leads and adapted to momentarily close the circuit of one or other of the windings of the said electromagnetic device according as the current passing through it rises above or falls below a predetermined amount.

10. In an alternating-current-distributing system, the combination with one or more main transformers, of a supplementary transformer, separate switches whereby the primary and secondary windings of the said supplementary transformer can be short-circuited or placed in series respectively with the primary and secondary windings of the main transformer or transformers, an electromagnetic device comprising a hollow cylindrical iron core, connected armature end plates arranged to move toward and from the respective ends of said core and connected to said switches, and two windings, and an electrically-controlled switch comprising a winding in the primary distributing-circuit, an armature arranged to be actuated when the current flowing through said switch-winding rises above or falls below a predetermined amount, two insulated contact-levers connected to the low-tension leads and arranged to be actuated quickly in one direction or the other when moved by said switch-armature, a pair of insulated stationary contacts connected to the outer ends of the two windings of the electromagnetic device and arranged in the path of one of the contact-levers, and a third stationary contact connected to the inner ends of the two windings and arranged in the path of the second contact-lever, substantially as described.

Signed at London, England, this 23d day of October, 1903.

ARTHUR FRANCIS BERRY.
